Percy T. Frost

UNITED STATES PATENT OFFICE.

PERCY T. FROST, OF EAST LIVERPOOL, OHIO, ASSIGNOR TO THE TRENLE CHINA COMPANY, OF EAST LIVERPOOL, OHIO, A CORPORATION OF OHIO.

DESIGN FOR A PLATE OR SIMILAR ARTICLE.

44,472.

Specification for Design.

Patented Aug. 12, 1913.

Application filed May 2, 1913. Serial No. 765,126. Term of patent 3½ years.

To all whom it may concern:

Be it known that I, PERCY T. FROST, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate, partially broken away, showing my new design.

I claim:

The ornamental design for a plate or similar article, as shown.

PERCY T. FROST.

Witnesses:

A. PICKIN,
ELIZABETH SMITH.
